CLAIM

The ornamental design for a phone case, as shown and described.

DESCRIPTION

FIG. 1 is an illustration of a front view of a phone case showing our new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is an isometric view of the back thereof; and,

FIG. 8 is an isometric view of the front of the phone case. The broken lines immediately adjacent the shaded surfaces represent the bounds of the claimed design. All other broken lines depict environmental subject matter that forms no part of the claimed design. The broken lines and unshaded regions bounded by broken lines form no part of the claimed design.
